US00D982790S

(12) **United States Design Patent** (10) **Patent No.:** **US D982,790 S**
Bourne (45) **Date of Patent:** **** Apr. 4, 2023**

(54) **FLASHLIGHT**

(71) Applicant: **Energizer Brands, LLC**, St. Louis, MO (US)

(72) Inventor: **Chris Bourne**, St. Louis, MO (US)

(73) Assignee: **Energizer Brands, LLC**, St. Louis, MO (US)

(**) Term: **15 Years**

(21) Appl. No.: **29/758,980**

(22) Filed: **Nov. 19, 2020**

Related U.S. Application Data

(62) Division of application No. 29/690,442, filed on May 8, 2019, now Pat. No. Des. 918,446.

(51) **LOC (14) Cl.** **26-02**

(52) **U.S. Cl.**

USPC **D26/37**

CLAIM

The ornamental design for a flashlight, as shown and described.

DESCRIPTION

FIG. 1 is a bottom front perspective view of a flashlight; FIG. 2 is a top rear perspective view, thereof;

FIG. 3 is a front view, thereof;

FIG. 4 is a back view, thereof;

FIG. 5 is a left side view, thereof;

FIG. 6 is a right side view, thereof;

FIG. 7 is a top view, thereof; and,

FIG. 8 is a bottom view, thereof.

The broken lines shown are provided for the purpose of illustrating environmental structure and form no part of the claimed design.

1 Claim, 7 Drawing Sheets
